RAILWAY TRUCK

Byers W. Kadel, Baltimore, Md., and Donald S. Barrows, Rochester, N. Y., assignors to The Symington-Gould Corporation, a corporation of Maryland

Application December 28, 1931, Serial No. 583,530

10 Claims. (Cl. 105—197.1)

This invention relates to railway vehicles and, more particularly, to the construction of the side frames, bolsters and spring nests thereof, for supporting the bolsters from said frames.

5 The principal object of our invention, generally considered, is the improvement in trucks for railway rolling stock, and particularly the side frames, bolsters and spring nests thereof, whereby the bolsters are efficiently supported by the associated side frames.

10 Another object of our invention is to provide a nest of bolster springs involving helical and elliptic springs, one or more of said springs being disposed above the remainder, whereby some 15 of the springs may be housed in the bolster, and the remaining spring, or springs, in the side frame.

20 A further object of our invention is the provision of a nest of helical and elliptic springs for supporting a bolster from an associated side frame, said springs being supported on said frame with one kind of springs above the other and/or positioned with the major axis of one kind transverse to that of the other kind of springs.

25 A still further object of our invention is the provision of a bolster adapted to be supported in the bolster openings of associated side frames, the ends of said bolster having pockets open at the bottom from end to end, said pockets being 30 bounded by parallel walls spaced transversely of said bolster and constituting guides for cooperating with associated elliptic springs, the outer ends of said bolster having side walls spaced transversely from said spring guiding 35 walls and adapted to engage bolster guide columns of associated frames, the walls of the spring pockets of said bolster being connected at the outer ends by webs extending transversely of said bolster.

40 Other objects and advantages of the invention relating to the particular arrangement and construction of the various parts will become apparent as the description proceeds.

45 Referring to the drawings illustrating our invention, the scope whereof is defined by the appended claims:—

50 Figure 1 is a partial side elevation of a railway vehicle or truck, particularly showing a portion of the side frame thereof with its associated bolster and a nest of springs.

55 Figure 2 is a transverse sectional view on the line 2—2 of Figure 1, looking in the direction of the arrows.

Figure 3 is a horizontal sectional view on the

line 3—3 of Figure 2, looking in the direction of the arrows.

Figure 4 is a transverse sectional view on the line 4—4 of Figure 1, looking in the direction of the arrows.

Figure 5 is a transverse sectional view corresponding with Figure 2, but showing a modification.

Figure 6 is a transverse sectional view corresponding to Figure 4, but showing another modification. 10

Referring to the drawings in detail, like parts being designated by like reference characters, and first considering the embodiment of our invention illustrated in Figs. 1 to 4, inclusive, there 15 is shown a portion of a railway vehicle or truck comprising side frames 1, only one of which is illustrated, each side frame comprising a compression member 2, a tension member 3, and bolster guide columns 4 spacing intermediate portions thereof and leaving a window or bolster opening 5 therebetween. The tension member 3 beneath the window opening is formed hollow to provide pockets or compartments 6 which, in the present embodiment, receive sets of helical 20 springs 7. Each set may comprise an outer coil 8 and an inner coil 9. The lower web of the tension member is desirably embossed downwardly 25 below the normal curved outline of the tension member, as indicated at 10, to provide the requisite area for seating said coils, either directly 30 on the frame or on spring plates 10'. The side walls 11 of the tension member beneath the window opening 5 are desirably formed with openings 12, preferably on the transverse axes of the 35 springs 7, which openings allow for inspection of said springs, as well as lightening the frame. The walls 11 of the tension member are desirably reinforced or beaded around said openings 12, as illustrated. 40

Normally supported by the springs 7 is an associated bolster 13, said bolster preferably having downwardly extending plugs 14 received in apertures 15 in the upper wall 16 of the pocketed portion of the tension member 3 for engaging 45 caps or plates 17 which, in turn, desirably rest on the tops of the springs 7, thereby providing for resiliently supporting the bolster 13. The plugs 14 are desirably hollow, as indicated at 18, and receive the upper end portions of cylindrical centering devices 19, said devices being desirably supported on the followers 17 by means of collars 20, and the lower portions received in the inner coils 9 of the spring units 7. 50

To increase the capacity of the bolster springs, 55

additional spring means 21 is desirably employed, said means, in the present embodiment, comprising elliptic springs supported by or engaging the upper wall 16 of the portion of the tension member 5 beneath the window opening 5, with its center desirably disposed in or substantially in the longitudinal central plane of the frame, and supportingly engaging the lower surface of the upper wall 22 of the bolster 13. In order to properly receive or house the springs 21, the bolster 13 desirably has at each end a recess or pocket 23. In the present embodiment, each recess or spring pocket 23 is defined by the upper wall 22, side walls 24, a wall 25 connecting the side walls and extending transversely of the bolster or approximately parallel to the associated side frame, and a depending outer wall or flange 26 serving to connect the side walls 24.

Each spring pocket 23, by being freely open 20 from below and bounded by parallel walls spaced transversely of the bolster or lengthwise of the side frames, provides for the free insertion or removal of the elliptic springs 21, the walls 26 being desirably so spaced that they constitute 25 guides for cooperating with the elliptic springs and, specifically, the center and end clips 27 and 28, respectively. The web or flange 26 defining the outer end of each spring pocket extends 30 transversely of the bolster above the major axis or mid horizontal plane of the elliptic springs, in the embodiment illustrated. The upper web or wall 22 of the bolster is desirably formed with depending lugs 29 normally lying on either side of the spring clips 27 and the upper web 16 of 35 the tension member beneath the window opening being correspondingly formed with upwardly extending lugs 30, thereby providing for properly centering the springs 21.

Referring now to the embodiment of our invention illustrated in Figure 5, there is shown a portion of a railway vehicle or truck comprising side frames 1^a, only one of which is illustrated, each side frame having a compression member 2^a, a tension member or portion 3^a, and spaced 40 connecting struts, bolster guide columns or portions 4^a spacing intermediate portions of said compression and tension members, and leaving a bolster opening 5^a therebetween. The construction is identical with that described in connection with the embodiment of Figures 1 to 4, 50 inclusive, except that the resilient means or spring units 21^a are shorter or smaller in vertical dimension than the spring units 21 of the preceding embodiment, or there is initially a space 55 between them and the upper web of the bolster 13^a, so that said bolster or member 14^a, extending through a slot in a spring housing portion of the tension member 3^a, is initially supported by the coil or lower springs 7^a which are in turn 60 supported by the lower web portion 10^a of the tension member. The elliptic or leaf springs 21^a are, therefore, not engaged until after a predetermined movement of the bolster or load-carrying member 13^a.

Referring now to the embodiment of our invention illustrated in Figure 6, there is shown a portion of a railway vehicle or truck comprising side frames 1^b, only one of which is illustrated, 70 each frame having a compression member or portion 2^b, a tension member or portion 3^b and spaced connecting struts 4^b, leaving a window or bolster opening 5^b therebetween. The construction and arrangement is identical to that 75 shown in Figures 1 to 4, inclusive, except that

the bolster 13^b is initially supported entirely on the elliptic or leaf springs, corresponding to the springs 21 of the first embodiment, but not here illustrated, with the bolster extensions 14^b spaced from the supporting surfaces provided above the 5 coil springs 7^b, which springs in turn rest on the lower web portion 10^b of the tension member 3^b. Thus the coil springs 7^b do not function until after a predetermined movement of the bolster or load-carrying member 13^b, or until the plug 10 or extension 14^b of the bolster comes into engagement with the tops of the coil spring means or cap 17^b thereof.

From the foregoing disclosure, it will be seen that we have provided a railway vehicle or truck 15 involving side frames, only one of which is shown, each receiving an end of an associated bolster in window openings thereof, each end of the bolster being supported by elliptic and helical springs acting simultaneously or in parallel. Although the present embodiment shows the elliptic spring means as comprising full elliptic springs, each consisting of a pair of semi-elliptic springs, it will be understood that we do not wish to be limited to the exact showing, as the mere omission of a part of the nest of springs would not affect the combination as defined in the appended claims. The bolster has a suitable pocket 20 at each end for receiving one or more springs bearing directly upon the elevated upper web 30 portion of the tension member beneath the window opening. The lower spring or springs are actuated by a plug or plugs depending from the bolster, and the actuation of the helical and elliptic springs may be simultaneous unless it is desired 35 to compress one or the other type of spring a predetermined amount before simultaneous action begins.

Although we have described a preferred embodiment of our invention, it will be understood 40 that modifications may be made within the spirit and scope of the appended claims, the terms we have employed being used as those of description and not of limitation.

We claim:—

1. In a railway vehicle, in combination, a side frame formed with compression and tension members spaced at intermediate portions by guide columns, leaving a bolster opening therebetween, spring means seated on said tension member, and a bolster supported by said spring means, said bolster being provided at its end with a pocket for receiving said spring means, said pocket being opened below from end to end and bounded by parallel walls spaced longitudinally 50 of the side frame and constituting guides for the lowermost element of said spring means.

2. In a railway truck, a bolster comprising top and side walls and formed at its outer ends with spaced walls rigid therewith and positioned between said side walls, parallel to the bolster longitudinal axis, and elliptic springs guided between said spaced walls.

3. In a railway vehicle, the combination of a side frame having tension and compression members, spaced struts integrally connecting said tension and compression members and forming a window, said tension member forming a spring housing enclosing seats disposed longitudinally of the frame and with their centers spaced apart a 65 distance greater than that between the surfaces of said struts nearest to one another, said tension member carrying a seat intermediate and above said spaced seats, and a load-carrying member supported on said side frame by coil 70 75

- springs supported on said spaced seats, and leaf springs supported on said intermediate seat.
4. In a railway vehicle, the combination of tension and compression members, spaced integral connecting columns forming a window with said tension and compression members, said tension member having a spring housing disposed below said window, said housing having spaced seats therein and being slotted for communication with said window, coil springs on said seats, and a load-carrying member supported on leaf springs in said window and provided with members extending through slots and being arranged to engage said coil springs only after a predetermined movement of said load-carrying member. 5
5. In a railway vehicle, in combination, tension and compression members, spaced integral connecting columns forming a window with said tension and compression members, said tension member having a spring housing disposed below said window, said housing having spaced seats therein and being slotted for communication with said window, coil springs on said seats, a load-carrying member extending into said window and having portions extending through said slots and in engagement with said coil springs, and leaf springs in said window adapted to be engaged by said load-carrying member only after a predetermined movement thereof. 10
- 20
6. In a railway vehicle, in combination, a side frame formed with compression and tension members spaced at intermediate portions by guide columns, leaving a bolster opening therebetween, an elliptic spring comprising two sets of leaves held together by bands, with the lower band seated on said tension member, and a bolster supported by said elliptic spring, said bolster being provided at its end with a pocket defined by an upper wall directly engaging said upper band and receiving said elliptic spring, said pocket opening downwardly from end to end and bounded by parallel walls depending from said upper wall, spaced longitudinally of the side frame, and constituting guides for the lower band of said elliptic spring. 15
- 25
7. In a railway vehicle, in combination, a side frame formed with compression and tension members spaced at intermediate portions by guide columns, leaving a bolster opening therebetween, an elliptic spring comprising two sets of leaves held together by bands, with the lower band seated on said tension member, a bolster supported by said elliptic spring, said bolster being provided at its end with a pocket defined by an upper wall directly engaging said upper band and receiving said elliptic spring, said pocket opening downwardly from end to end and bounded by parallel 30
- 35
- walls depending from said upper wall, spaced longitudinally of the side frame, and constituting guides for the lower band of said elliptic spring, and helical springs supported on said tension member beneath the portion on which the elliptic 5

- 45
- 50
- 55
8. In a railway vehicle, a pair of side frames, a bolster with its ends received therein, said bolster comprising a top wall, spaced walls rigid therewith, depending therefrom, and disposed generally parallel to, and spaced substantially equal distances from, the longitudinal axis of said bolster, and leaf spring means substantially housed and guided between said spaced depending walls and comprising band means holding portions of said leaf spring means, said bolster having an abutment portion engaging said band means and defined by ribs spaced longitudinally 10

- of said bolster, movement of said band means transversely of said bolster being limited by said depending walls.
9. In a railway vehicle, in combination, a side frame formed with compression and tension members spaced at intermediate portions by guide columns, leaving a bolster opening therebetween, a bolster received in said opening, a nest of coil springs supported by said tension member and acting to support said bolster, and leaf springs, held together by band means, partially housed in said bolster, extending longitudinally thereof, and acting on said tension member through an abutment disposed above the plane of support of said coil springs by said tension member, the upper wall of said bolster having portions depending therefrom to center the upper portion of the band means of said leaf springs, and the longitudinal central plane of said leaf springs dividing the nest of coil springs into two equal parts. 25
